UNITED STATES PATENT OFFICE.

JOHN H. AHRENS, OF BROOKLYN, NEW YORK.

CASH-REGISTER.

SPECIFICATION forming part of Letters Patent No. 449,395, dated March 31, 1891.

Application filed October 21, 1890. Serial No. 368,851. (No model.)

To all whom it may concern:

Be it known that I, JOHN H. AHRENS, of Brooklyn, in the county of Kings, in the State of New York, a citizen of the United States, 5 have invented certain new and useful Improvements in Cash-Registers and Adding-Machines, of which the following is a specification.

This invention relates to improvements in 10 that class of machines that are used for registering and adding amounts.

The object of my invention is to provide a 15 machine of this kind which is simple in construction, reliable and quick in operation, and which automatically opens the money-drawer as soon as the machine is used to count, the closing of the drawer bringing the counting-hands back to the original position.

The invention consists in the combination, 20 with a casing, of a drawer, a spring for throwing the drawer outward, an adding mechanism in the casing, and a locking-lever operated by the adding mechanism and serving to lock the drawer in place.

25 The invention also consists in the construction and combination of parts and details, which will be fully described hereinafter, and finally pointed out in the claims.

In the accompanying drawings, Figure 1 is 30 a front elevation of my improved cash registering and adding machine. Fig. 2 is a vertical longitudinal sectional view on the line 2 2 of Fig. 4. Fig. 3 is a vertical longitudinal sectional view on the line 3 3 of Fig. 4. Fig. 35 4 is a horizontal sectional plan view on the line 4 4 of Fig. 2. Fig. 5 is a side view of the mechanism, the casing being shown in vertical transverse sectional view, parts being broken out; and Fig. 6 is a horizontal sectional view on the line 6 6 of Fig. 5.

Similar letters of reference indicate corresponding parts.

The counting mechanism is contained in a casing A, secured on a hollow base A', containing a drawer A², provided at the front with a suitable handle A³. To the inner surface of the rear wall of the hollow base A' a spring A⁴ is secured, which bears against the rear edge of the bottom of the drawer A² and 45 throws said drawer outward. The mechanism is secured to two standards B B', fastened on the base. In the front standard B the

sleeve C is mounted to turn, and through said sleeve C the arbor C' passes, the rear end of which projects from the back of the rear 55 standard B'. A handle or pointer D', having a handle-knob d', is secured to the front end of the arbor C', and a like but longer hand or pointer D, having a handle-knob d, is secured to the front end of the sleeve C. A 60 spiral spring E has one end secured to the sleeve C and its other end secured to a pin e, fastened on an arm B² of the front standard B. In a like manner a spiral spring E' is secured to the rear end of the arbor C', the 65 other end of said spiral spring E' being secured to the arm of the rear standard B' in the same manner as the end of the spring E is secured to the arm of the front standard B.

On the sleeve C a disk F is loosely mounted, and on its face is divided into one hundred parts along the circumference, which parts or subdivisions are numbered. A spring-pawl f on the disk F engages a toothed wheel G, fixed on the sleeve C, and to said toothed 70 wheel G another toothed wheel g is fixed, the teeth of the two wheels projecting in opposite directions. To said wheel g an arm G² is secured, the end of which can strike against a stop or lug B³ on the end of the arm B² on 75 the front standard B.

On the arbor C' a disk F' is loosely mounted, which is provided on its face along the rim with fifty subdivisions, and a spring-pawl f' on said disk engages a toothed wheel G', 85 fixed on the arbor C', and to said toothed wheel G' a toothed wheel g' is fastened, the teeth projecting in opposite directions. There are as many teeth on the wheels G g as there are subdivisions on the disk F and as many 90 teeth on the wheels G' g' as there are subdivisions on the disk F'. To the wheel g' is fastened an arm G³, that is adapted to strike against a stop-lug G⁴ on a standard G⁵ of the machine-frame. To the back of 95 the disk F is fastened a tooth or lug H, that is adapted to engage the teeth of a wheel h, having twenty teeth, each of which is numbered, said toothed wheel h having a fixed lug h', adapted to engage the toothed wheel 100 h², having twenty teeth. Said wheels h and h² are mounted on an arm B⁵ of the front standard B. The disk F' is provided with a lug or tooth H', adapted to engage the teeth

of a wheel H^2 , having twenty teeth, said wheel H^2 being fixed on a suitable shaft mounted in the standards B and B'. Spring-pawls h^3 , h^4 , and h^5 engage the teeth of the 5 wheels h^2 , H^2 , and h^2 , respectively. The pointers J and J' are arranged to point to the numerals on the disks F and F', respectively, and the pointers J², J³, and J⁴ are arranged to point to the subdivisions on the wheels h^2 , h , 10 and H^2 , respectively. A spring-pawl lever K, pivoted to the front standard R, has its upper toothed end so arranged that the same can engage the teeth on the toothed wheel g' in front of the disk F'. The lower ends of 15 said levers project into the hollow base and are adapted to be acted upon by the two cam-lugs L and L', projecting upward from the bottom of the drawer A².

On the inner end of the sleeve C a disk M 20 is mounted, and adjacent to the same a like disk M' of the same size is fixed on the arbor C', both of said disks being provided with the notches N, which are tapered at one side. Into said notches N the tooth O is adapted to 25 snap, which projects from the upper end of the locking-lever P, the lower end of which lever is adapted to engage the shoulder Q on a cam-lug R, extending upward from the bottom of the drawer. A suitable spring S, acting 30 on the upper end of the lever P, keeps the tooth on the upper end of said lever in contact with the edges of both disks M and M'. The front of the casing A is provided with a dial having the two circles T and U, 35 of which the former is divided into fifty parts and the latter into one hundred, the said circles being so arranged that the end of the pointer D' travels over the circle T and the end of the pointer D travels over the circle 40 U. Each subdivision of the circles T U is provided with an aperture m', adapted to receive a check-pin n, fastened to a chain or cord o, which in turn is secured to the side of the casing. The lower parts of the circles 45 T U of the dial are provided with a hinged section W on the front of the casing. By raising said wing or lower hinged section W the numbers indicated by the pointers J, J', J², J³, and J⁴ on the disks F F' and wheels h , 50 h^2 , and H^2 can be examined. The wing W is provided with a lock W'. The large hand or pointer D is used to register cents and the smaller one D' is used to register dollars.

The operation is as follows: Both pointers 55 or hands D D' are at zero on the circles T U, and the pointers J, J', J², J³, and J⁴ point to zero on the disks F F' and the wheels h^2 , h , and H^2 . The drawer is within the casing and is locked in place by the locking-lever P, the 60 lower end of which engages the shoulder Q on the cam-lug R, fixed in the drawer. The drawer cannot be pulled out when thus locked. If a certain amount of money is to be deposited—for example, twenty-three cents—the 65 operator places the pin n into the aperture m in the subdivision 23 on the outer circle U, and then the hand or pointer D is moved in

the direction of the arrow x', Fig. 1, until it strikes against the pin n in the aperture m of the subdivision 23 on the outer circle U, 70 where it remains, thus indicating that the attendant has registered twenty-three cents. As soon as the hand or pointer D is turned in the direction indicated the corresponding disk M is rotated in the direction of the 75 arrow x', Fig. 1, and presses the upper end of the locking-lever P outward—that is, to the right—whereby the lower end of the lever is moved to the left and is disengaged from the shoulder Q on the cam-lug R, thus permitting 80 the spring A⁴ to throw the drawer outward, so as to permit the attendant to deposit the coins in the same. The toothed wheel G is turned by the hand D, and as it engages the pawl f the disk F is rotated a distance 85 corresponding to the distance that the hand or pointer D is turned. The pawl-lever K, engaging the toothed wheel g, locks the several parts in place. After the money has been deposited the drawer is pushed inward, and 90 as the cam-lug L strikes the lower end of the pawl-lever K it moves the lower end of the same to the left, thereby moving the upper end to the right and disengaging it from the toothed wheel g, permitting the 95 spring E, which was brought into greater tension by turning the hand D in the direction of the arrow x', to throw the sleeve C, toothed wheels G g, and the pointer D back in the inverse direction of the arrow x' until the 100 pointer D is at zero of the circle U again. The arm G² strikes against the stop-lug B³, thereby preventing the spring from throwing the hand D farther in the inverse direction of the arrow x' than the zero of the circle U. 105 The disk F remains in the position into which it was brought by the turning of the hand D in the direction of the arrow x'. If another amount—for example, eighteen cents—is to be deposited, the above operation is repeated. 110 As soon as the hand D is turned, and if it is turned only the distance of one subdivision, corresponding to one cent, the drawer is released and thrown outward, and as soon as the drawer is pushed back the toothed wheel 115 g is released and the hand brought back into position by the action of the spring E. If dollars are to be recorded, the pin n is placed into one of the apertures m of the circle T, and the smaller hand D' is turned in the manner described, and in the same way releases the drawer, as the wheel M' now acts on the locking-lever P, and when the drawer is pushed back the cam-lug L', acting on the lever K', disengages said lever from the toothed 125 wheel g', permitting the spring E' to throw the hand D' back into its original position. Every time the disk F makes one complete revolution, corresponding to one dollar, the wheel h is rotated the distance of one tooth, 130 and every time the wheel h makes one complete revolution, corresponding to twenty dollars, its lug h' rotates the wheel h^2 the distance of one tooth, corresponding to twenty

dollars. Every time the disk F' makes one complete revolution, corresponding to fifty dollars, the wheel H² is rotated one tooth, and so on. The contents of the drawer must correspond to the amount indicated by the pointers J, J', J², J³, and J⁴ on the disks F and F' and the counting-wheels h, h², and H². To verify the account, the wing W is unlocked and raised, and the positions of the pointers J, J', J², J³, and J⁴ of the several wheels are noted.

Having thus described my invention, I claim as new and desire to secure by Letters Patent—

15 1. In a cash registering and adding machine, the combination, with a casing, of a drawer, two independent concentric adding-disks, means for rotating them independently of each other, an independent locking-disk connected with each adding-disk, a locking-lever engaging both of said locking-disks, and a projection on the drawer engaging said locking-levers, substantially as set forth.

2. In a cash registering and adding machine, the combination, with two independent concentric adding-disks, of independent means for rotating them, a toothed wheel connected with each disk, a lever engaging said toothed wheel, and a drawer in the casing 30 and cam projections in the drawer, said cam projections being adapted to act on the pawl-levers, substantially as set forth.

3. In a cash registering and adding machine, the combination, with two independent concentric adding-disks, of a locking-disk connected with each adding-disk, a locking-lever adapted to engage both adding-disks, a drawer in the casing supporting the adding mechanism, a shouldered lug adapted to 40 engage the locking-lever, a toothed wheel connected with each adding-disk, a pawl-lever engaging each toothed wheel, and independent cam projections in the drawer adapted to act on said pawl-levers, substantially as set forth.

45 4. In a cash registering and adding machine, the combination, with two independent concentric adding-disks, of a sleeve on which one disk is mounted, an arbor passing through

said sleeve and on which the other disk is mounted, a spring connected with the sleeve, a spring connected with the arbor, means for turning said sleeve and arbor independently of each other, toothed wheels connected with the adding-disks, pawl-levers engaging said toothed wheels, and a sliding drawer and projections on the drawer adapted to act on said pawl-levers, substantially as set forth.

5. In a cash registering and adding machine, the combination, with the sleeve C and arbor C', of the disks F F', mounted to turn on the sleeve and arbor, the toothed wheels G g on the sleeve C, the toothed wheels G' g' on the arbor C', the spring-pawl f f' on the disks F F', engaging the toothed wheels G G', 60 the springs E and E', acting on the sleeve and arbor, the stop-lugs B³ G¹, against which said arms can rest, the pawl-levers K, a sliding drawer, and projections in the drawer adapted to act on the pawl-levers, substantially as set forth.

6. In a cash registering and adding machine, the combination, with two concentric and independent adding-disks F F', of the independent hands D D' for turning said 75 disks, the pointers J J', projecting over the faces of said disks, the counting-wheels h h², operated from the disk F, the pointers J² and J³, projecting over said wheels h h², the wheel H², operated from the disk F', and the pointer J⁴, projecting over said wheel H², substantially as set forth.

7. In a cash registering and adding machine, the combination, with a casing, of a drawer, a spring for throwing the drawer outward, a counting mechanism, a lever engaging said counting mechanism, which lever serves for locking the drawer in closed position, and a cam projection in the drawer adapted to engage said lever, substantially 90 as set forth.

In testimony that I claim the foregoing as my invention I have signed my name in presence of two subscribing witnesses.

JOHN H. AHRENS.
